ATTORNEY

UNITED STATES PATENT OFFICE

139,202

DESIGN FOR A REFRIGERATED DISPLAY CABINET

Alfred Beaudry, Los Angeles, Calif.

Application August 1, 1944, Serial No. 114,673

Term of patent 7 years

(Cl. D80—11)

To all whom it may concern:

Be it known that I, Alfred Beaudry, a citizen of the United States, residing at Los Angeles, in the county of Los Angeles and State of California, have invented a new, original, and ornamental Design for a Refrigerated Display Cabinet, of which the following is a specification, reference being had to the accompanying drawing forming part thereof.

Figure 1 is a front view in perspective of the refrigerated display cabinet embodying my new design; Fig. 2 is a perspective view of the rear thereof.

I claim:

The ornamental design for a refrigerated display cabinet, as shown.

ALFRED BEAUDRY.
